BUTTONHOLE ATTACHMENT

Charles R. Thomas, Wayland, Mass., assignor to The Greist Manufacturing Company, New Haven, Conn., a corporation of Connecticut

Application May 29, 1957, Serial No. 662,387

15 Claims. (Cl. 112—77)

This invention relates to a sewing machine attachment and particularly an attachment for making buttonholes. The attachment illustrated is designed for use with the ordinary household sewing machine and to that end may be attached to the presser bar of the sewing machine when the presser foot is removed and a lever carried by the device is connected to the needle bar so that this lever which actuates the mechanism of the attachment is in turn actuated by reciprocation of the needle bar.

In an attachment for making buttonholes, it is desirable to employ a cloth-feeding member or foot which will move the cloth in an oblong path in order that stitching may be effected around the periphery of the buttonhole and at the same time effect movement of the cloth in a zigzag path to effect the individual stitches over the edge of the buttonhole. In moving the cloth in the oblong path the feed blade is moved to and fro in a step-by-step movement, and at each end of such movement the cloth should be moved from one side to the other in order to stitch on one side of the buttonhole during movement in one direction and upon the opposite side of the buttonhole during movement in the other direction.

It is also desirable in attachments of this character to provide for adjustment of the zigzag movement of the feed blade so that the amplitude of these movements may be varied according to the size of the buttonhole which is being made. Further means should be provided for adjustment of the length of the buttonhole and for adjustment of the shape of the buttonhole, the latter being necessary for the reason that at times it is desired to make a plain oblong buttonhole and at other times a buttonhole of keyhole shape or one enlarged at one end. In former attachments of this character the size and shape of the buttonhole have been determined by providing a template or toothed rack which serves as the guiding member for the feed blade. As the size and shape of the template or rack serve to determine the size and shape of the buttonhole, a number of such templates or racks have been provided of different shape and sizes which may be removably attached to the feed blade so that one may be replaced by another, depending upon the size and shape of the buttonhole which is desired.

In the present construction a single main template is provided together with two auxiliary templates, one at each end of the toothed opening or rack in the main template. One of these auxiliary templates may be adjusted relatively to the main template to adjust the effective length of the latter so as to vary the length of the buttonhole. The other auxiliary template is of a shape different from the adjacent end of the main template so that it may be adjusted in and out of an operative position so as to provide the necessary guide for the feed blade to change the shape of one end of the buttonhole. That is to say, if the opening in the main template is of keyhole shape as is presently illustrated, the auxiliary template will be of oblong shape so that when it is moved to operative position a plain oblong buttonhole will result, while,

2

if the auxiliary template is moved to inoperative position, a buttonhole of keyhole shape will be effected.

Moreover, in the present construction all of the templates are permanent parts of the mechanism and are not intended to be removed and replaced by others. Therefore, adjustment of the length or shape of the buttonhole may be readily made by adjustment of these auxiliary templates, which adjustment may be easily effected by the manipulation of turn buttons or the like.

10 Thus the resulting attachment is one which may be readily used and adjusted by an inexperienced user of a sewing machine without the labor of changing one part for another, and there are no loose or separate parts to become lost or mislaid.

15 One object of the present invention is to provide a new and improved sewing machine attachment for making buttonholes.

20 A further object of the invention is to provide a new and improved buttonhole attachment for domestic sewing machines whereby the shape of the buttonhole to be made may be varied by a simple manipulation of the parts of the device.

25 Still another object of the invention is to provide an improved buttonhole attachment for domestic sewing machines wherein the size of the buttonhole may be easily varied.

30 Still another object of the invention is the provision of a buttonhole attachment for sewing machines wherein the size and shape of the buttonhole to be made may be readily varied by the user without the necessity of replacement or interchange of any of the parts of the mechanism.

35 Still another object of the invention is the provision of a buttonhole attachment for ordinary household sewing machines wherein the size and shape of the buttonhole are determined by a main template and auxiliary templates, one of the latter being associated with one end of the main template and adjustable with respect thereto to determine the size of the resulting buttonhole, and the other being associated with the other end of the main 40 template and adjustable with respect thereto to determine the shape of the resulting buttonhole.

45 To these and other ends the invention consists in the novel features and combinations of parts to be herein-after described and claimed.

45 In the accompanying drawings:

Fig. 1 is a side elevational view of a buttonhole attachment embodying my invention;

Fig. 2 is a top plan view thereof;

Fig. 3 is an elevational view showing the side opposite that shown in Fig. 1;

Fig. 4 is a vertical sectional view on line 4—4 of Fig. 2;

Fig. 5 is a horizontal sectional view on line 5—5 of Fig. 1;

55 Fig. 6 is an enlarged sectional view on line 6—6 of Fig. 1;

Fig. 7 is a transverse sectional view, somewhat enlarged, on line 7—7 of Fig. 2;

60 Fig. 8 is an enlarged sectional view of the mechanism at one end of the attachment, the section being in substantially the same plane as Fig. 4, but showing the parts in another position;

Fig. 9 is a view similar to Fig. 6 but showing the parts in the position of Fig. 8;

65 Fig. 10 is a perspective view of the length adjustment template;

Fig. 11 is a perspective view of the shape adjustment template;

Fig. 12 is a top plan view of the main template;

Fig. 13 is a bottom plan view of the guide plate; and

Fig. 14 is a perspective view of the bracket carrying the track sector.

To illustrate one embodiment of my invention I have shown in the drawings a base plate 10 having supported thereon a U-shaped frame structure comprising a horizontal body portion 11 and upstanding side flanges or walls 12. The body portion 11 of this frame structure is held in spaced relation to the base plate 10 by means of the laterally extending feet 13 which are downwardly offset from the plane of the body portion and are riveted to the base plate adjacent their ends, as shown at 14. Between the upstanding side flanges 12 is secured the adaptor 15 by which the device may be secured to the presser bar of the sewing machine.

Between the member 11 and the base plate 10 is slidably mounted the feed blade 16 which, as shown in Fig. 5, extends rearwardly substantially the entire length of the base plate. At its forward end the feed blade is provided with projecting feet 17 having downwardly extending ends 18 to which the feeding foot 19 is pivotally secured.

An actuating or driving lever 20 is pivoted to the member 11 at 21 and at its forward end this lever is provided with an upstanding roller cam follower 22 adapted to be engaged in the sinuous cam passage 23 of an internal cam member 24 secured upon a shaft 25 rotatably mounted in the side flanges 12.

As shown in Fig. 1 a ratchet wheel 26 is secured to the shaft 25. A fork arm 27 is rotatably mounted with respect to the shaft 25 and carries a pawl 28 pivoted to the fork arm at 29 and the free end of this pawl is urged into engagement with the teeth of the ratchet wheel 26 by a spring 30. The fork arm, as is understood, is adapted to be attached to the needle bar of the sewing machine so that upon reciprocation of the needle bar the shaft 25 and, therefore, the cam 24 will be rotated in a step-by-step movement, thus oscillating the lever 20 about its pivot 21.

It may here be explained that the feed blade 16 is not only slidably mounted with respect to the base plate 10, but is also pivoted with respect to this plate. To this end the feed blade is provided with an elongated slot 32 which receives the lower end of a pin 33 having an enlarged shoulder 34 slidably engaged in a slot 35 in the body member 11 of the frame. Thus the feed blade may oscillate about the pin 33 as well as move in a longitudinal direction with respect to this pin by virtue of the slot 32.

The upper end of the pin 33 is secured to a slide 36 (Figs. 2 and 4), which slide is provided with an arm 37 extending laterally from its body portion, and this arm is provided with a downwardly depending flange 38. An adjusting button 39 is threaded into the flange 38, as shown at 40 (Fig. 4), and this button is slideable in a slot 41 in an upwardly extending flange 42 formed integrally with the base plate 10. The adjusting slide 36 is also provided with a slot 43 to receive a portion of the pivot member 21 (which is secured to the body member 11) so that the slide 36 will be properly guided in its movements. It will be seen that adjustment of the slide 36 as permitted by the slot 41 in the flange 42 will adjust the position of the pivot pin 33 with respect to the slot 32 in the feed blade and, therefore, will adjust the position of the pivot about which the feed blade is oscillated with respect to the cloth-engaging foot 19. This will vary the lateral or zigzag throw of the feeding foot.

The lever 20 extends rearwardly of the pivot 21 and secured to the upper surface thereof and in spaced relation thereto is a frame member 45. A short vertical shaft 46 is rotatably mounted in this member and in the rear end of the lever 20 to which shaft is secured a ratchet wheel 47. The teeth of this ratchet wheel are adapted to be engaged by a pawl 48 pivoted at 49 upon a transverse member 50 secured upon the flanges 42 and 42^a of the base plate in spaced relation to the latter. A spring 51 urges the pawl into engagement with the ratchet wheel. Also a stop pawl 53 is pivoted at 54 upon the lever 20

and also urged into engagement with the ratchet wheel by the spring 55.

It may here be noted that the shaft 46 and ratchet wheel 47, being carried by the lever 20, will be oscillated upon step-by-step rotation of the cam 24 and, as the pivot 49 of the pawl 48 is fixed with respect to the base plate, the pawl will effect rotation of the ratchet wheel when the lever is shifted in a counterclockwise direction or toward the top of the sheet, as shown in Fig. 5. When the lever 20 is oscillated in the opposite direction or clockwise, as viewed in Fig. 5, about its pivot 21, the holding pawl 53 will prevent rotation of the ratchet wheel in the opposite direction. A guide lug 20^a (Figs. 4 and 8) is secured to the lever 20 and extends below the member 50 to guide the lever in its movements.

Mounted in an elevated position upon posts 57 adjacent the rear end of the feed blade 16 is a housing comprising a bottom plate 58 and a top plate 59. These plates are spaced apart vertically, and between them is mounted the mechanism for effecting proper movements of the feed blade. This housing is, as shown in Fig. 4, mounted above the member 45, and the lower and upper plates 58 and 59 are held in spaced relation by side plates 60 (Fig. 7).

The shaft 46 extends upwardly through an opening 58^a in the lower plate 58 and secured upon this shaft is a pinion 61 (Figs. 4 and 8). As shown in Fig. 8, this shaft is hollow and is provided with a pin 62 which slidably supports thereon a plunger or follower 63 urged upwardly by a spring 64 which surrounds the pin 62. The pinion 61 cooperates with an adjustable template assembly, and the plunger 63 likewise cooperates with a guide plate, both to be hereinafter described.

Slidably mounted upon the lower plate 58 of the elevated housing is a main template 65 shown in top plan view in Fig. 12. This template is provided with internal rack teeth 66, these teeth being arranged in key-hole form at one end, as shown at 67, but being omitted at the other end of the template as shown at 68. A laterally projecting arm 69 formed integrally with the template is provided with an upwardly facing series of rack teeth 70.

Also the template is provided with a projecting guide finger 71 at one end adapted to be guided in a recess 72 in the upper surface of the lower plate 58. At its other end this main template is provided with an attaching finger 73 having a recess 74 in its upper surface. This recess is adapted to receive an arm 75 of a U-shaped connecting member 76 (see Figs. 8 and 14), the connecting member being secured to the template by screws 77. On the lower face of the template is provided a rib 78 guided in a groove 79 in the lower plate 58. As shown in Fig. 8, the pinion 61 is in mesh with the rack teeth 66 of the template 65.

Also slidably mounted between the members 58 and 59 and resting upon the template 65 is an auxiliary shape-adjusting template member (see Figs. 8 and 11) designated as a whole by the reference numeral 80. This template is provided with a substantially semi-circular series of rack teeth 81 which are adapted to be moved relatively to the rack teeth 66 so that the rack teeth 81 cover the teeth 67 and convert the end of the rack member 65 into plain oblong form instead of keyhole form. The auxiliary template 80 is provided at one side with a series of rack teeth 82 which, as shown in Fig. 7, stand in vertical spaced relation to the rack teeth 70 upon the template 65.

A pinion 83 (Fig. 7) is secured to a horizontal shaft 84 rotatably mounted in an L-shaped bracket 85 secured to the upper plate 59 of the housing and a spring 86 acting against the turn button 87 secured upon this shaft normally maintains the pinion in an outward inoperative position. The pinion lies between the rack teeth 82 and 70 upon the templates 65 and 80 and is adapted,

when rotated, to move the templates in opposite directions. A pin 87^a (Fig. 9) secured to the bracket 85 normally engages the pinion 83 and prevents accidental rotation thereof. When the push button 87 is pushed inwardly against the force of the spring 86, the pinion is freed from this pin.

A second auxiliary template 88 is provided (see Figs. 8 and 10), this template carrying a substantially semi-circular series of rack teeth 89 adapted to cooperate with the left-hand end of the rack teeth 66 and form a curved end portion for the latter. The template 88 is slidably mounted in the elevated housing and rests upon the template 65. It is also provided at one edge with a series of rack teeth 90 and, as shown in Figs. 1 and 9, these rack teeth are engaged by those of a pinion 91 secured to a vertical shaft 92 rotatably mounted in the lower and upper plates 58 and 59 and urged upwardly by a spring 93. A turn button 94 is fixed to the shaft 92 by which it may be rotated and, when this turn button is rotated, rotation of the pinion 91 will effect movement of the auxiliary length-adjustment template 88. This will move the internal rack teeth 89 relatively to the rack teeth 66 of the template 65 and vary the effective length of the latter.

A pointer 96 may be secured to the button 94 which may cooperate with indicia on the upper plate 59 to indicate the adjusted effective length of the rack 66. The shaft 92 is normally prevented from rotation by means of a pin 91^a which is secured to the upper plate 59 of the elevated frame and engages the teeth of the pinion 91. Depression of the button 94 against the action of the spring 93 releases the pinion from this pin and permits rotation thereof.

Secured to the undersurface of the upper plate 59 of the elevated frame by pins 97 is a guide plate 98 shown in Fig. 13. The auxiliary templates, that is, both the shape-adjusting template 80 and length-adjusting template 88, are slidably mounted between this guide plate and the main template 65. This guide plate is provided on its undersurface with guiding grooves 99 in which slide ribs 100 (Fig. 11) on the template 80. Similarly grooves or recesses 101 are provided in the plate for ribs 102 (Fig. 8) on the upper surface of the template 88. These grooves 101 are also guiding grooves for the plunger 63 carried by the shaft 46 of the pinion 61 so that as the pinion is rotated and the template 65 together with the elevated frame and feed blade is moved longitudinally, the plunger 63 will follow about the grooves 101.

These grooves are separated by a rib 103, a portion of which is omitted at the right-hand end of the template 65, as shown at 104, so that the plunger may travel about the end of this rib and pass from one of the grooves 101 into the other. In order to permit the plunger to cross over the rib at the left-hand end of the guide plate, as shown in Fig. 13, the forward ends of the ribs 102 are beveled on their undersurfaces, as shown at 105, so that, when the plunger reaches one of these bevels or ramps 105, it will be depressed into the arcuate passage 106 provided within the rack teeth 89, and thus be guided from one side to the other of the rack 66. A lug 107 may be provided to maintain the pin in the recess 100 during this travel.

At the other end of the template 65 the plunger 63 travels in the circular shaped end 108 of the grooves 101 through the opening 104. However, when the template 80 is in its inoperative position and the pinion 61 travels around the keyhole shaped end 67 of the rack 66, means are provided to insure that the plunger is pushed outwardly away from the rib 103. To this end the member 76 (Fig. 14) is provided with an arm 109 which extends over the upper plate 59 and guide plate 98 and is provided with a sector 110 having a slot 111 to receive

the rib 103 or the extension rib 103^a depending upon the position of the member 76 which, as will be remembered, is secured to the template 65.

The guide plate 98 (Fig. 13) is provided with a recess 112 which registers with a recess 113 in the upper plate 59 so that the sector 110 extends downwardly through these openings to engage the ribs 103 and 103^a. When the template 65 is drawn to the right, as shown in Figs. 4 and 6 of the drawings, for example, and the auxiliary template 80 is moved to the left to cover the keyhole end 67 of the rack 65, the member 76 is also drawn to the right and is positioned over the rib 103^a, thus permitting the plunger 63 to follow through the opening 104 closely adjacent the end of the rib 103. However, when these two templates are moved in the reverse direction, as shown in Figs. 8 and 9, the sector 110 is moved to the left over the end of the rib 103, as shown in Fig. 9, so that the plunger and pinion will be forced outwardly from the rib 103 and compelled to travel around the end of the rack of keyhole shape.

Means are provided for operating the shaft 46 manually when desired. To this end an arm 115 is journalled upon the shaft 46 below the ratchet wheel 47 and upon this arm is pivoted at 116 a pawl 117 urged by spring 118 into engagement with the teeth of the ratchet wheel. The user by manually oscillating the arm 115 may, therefore, rotate the shaft 46 in a step-by-step movement and move the feed blade to any desired position.

It is believed that the operation of the device will be evident from the foregoing description. It will be noted that all of the usual adjustments desired in an attachment of this type are provided in an assembled structure and that not only the shape but the length of the buttonhole to be made may be adjusted without the necessity of detaching and replacing any of the parts.

As previously described, the length of the buttonhole may be adjusted by rotation of the button 94 (Fig. 1) which will move the template 88 (Fig. 10) relatively to the template 65 so as to move the rack teeth 89 over the teeth 66 of the template 65 toward and from the rounded end portion 67 of the latter rack. As the rack teeth 89 determines the left-hand end of the rack 65, the distance of this member from the right-hand end will, of course, determine the length of the buttonhole and the template 88 is, therefore, the length-adjusting member.

If it is desired to make a buttonhole of keyhole shape, the turn button 87 is pushed inwardly to release the pinion 83 from the pin 87^a and is then turned in the right direction to move the template 65 to the left and the template 80 to the right, thus exposing the end 67 of the rack 66. During movement of the rack 66 to the left, the sector 110 will also be moved to the left and engage over the right-hand end of the rib 103. If it is desired to make a buttonhole of plain oblong shape, the turn button 87 will be rotated in the opposite direction and the template 65 moved to the right and the template 80 to the left so that the rack teeth 67, as shown in Fig. 6, and thus arrange the device for a buttonhole of plain oblong shape.

While I have shown and described one embodiment of my invention, it will be understood that it is not to be limited to all of the details shown, but is capable of modification and variation within the spirit of the invention and within the scope of the claims.

What I claim is:

1. In a buttonhole attachment for sewing machines, a supporting plate, a feed blade mounted thereon for oscillatory and sliding movements, a lever pivotally mounted on the plate, a pinion rotatably mounted on said lever, a template structure carried by the feed blade, said structure comprising superposed main and auxiliary templates, said main template having an internal rack member of generally oblong shape, said auxiliary

template having an internal rack member of arcuate shape, and disposed adjacent one end of said first rack member, said templates being mounted for relative movement in a linear path, means for effecting relative movement of said templates to cause said second rack member to move toward and from the remote end of said second rack member, said pinion being in mesh with the teeth of said rack members, means for rotating said pinion, and means for guiding said pinion around said rack members to effect movements of the feed blade.

2. A buttonhole attachment as in claim 1 wherein the means for effecting relative movement of the templates comprises a series of teeth on one template and a manually rotatable pinion engaged with said teeth.

3. A buttonhole attachment as in claim 1 wherein the means for effecting relative movement of the templates comprises a series of teeth on one template and a rotatable pinion engaged with said teeth, and wherein releasable means is provided normally holding said pinion against rotation.

4. In a buttonhole attachment for sewing machines, a supporting plate, a feed blade mounted thereon for oscillatory and sliding movements, a lever pivotally mounted on the plate, a pinion rotatably mounted on said lever, a template structure carried by the feed blade, said structure comprising superposed main and auxiliary templates, said main template having an internal rack member of generally oblong shape but being enlarged at one end in keyhole form, said auxiliary template being provided with an internal rack member of arcuate shape disposed adjacent, but beyond, the enlarged end of said first-named rack member, said templates being mounted for relative movement in a linear path, means for effecting relative movement of said templates to move said second rack member to a position inwardly of the enlarged end of said first rack member, the pinion being adapted to mesh with the teeth of said rack members, means for rotating said pinion, and means for guiding said pinion around said rack members to effect movements of the feed blade.

5. In a buttonhole attachment for sewing machines, a supporting plate, a feed blade mounted thereon for oscillatory and sliding movements, a lever pivotally mounted on the plate, a pinion rotatably mounted on said lever, a template structure carried by the feed blade, said structure comprising superposed main and auxiliary templates, said main template having an internal rack member of generally oblong shape but being enlarged at one end in keyhole form, said auxiliary template being provided with an internal rack member of arcuate shape disposed adjacent the enlarged end of said first rack member, supporting means in which said templates are slidably mounted for movement relatively to each other in a linear path, means for effecting sliding movements of the templates in opposite directions simultaneously, means for rotating said pinion and means for guiding said pinion around said rack members to effect movements of the feed blade.

6. A buttonhole attachment as in claim 5 wherein the means for effecting slidable movements of the templates comprises a series of teeth on each of said templates disposed in spaced relation and a pinion, rotatably mounted on the template-supporting means, extending between, and engaged with both of, said series of teeth.

7. A buttonhole attachment for sewing machines comprising a supporting plate, a feed blade mounted thereon for oscillatory and sliding movements with respect thereto, a lever pivotally mounted on said plate, a pinion rotatably mounted on said lever, a supporting structure carried by the feed blade, a main template slidably carried by said structure, a pair of auxiliary templates slidably mounted in said structure for movement each in a linear path relatively to the main template, one adjacent each end of said main template, each of said templates being provided with an internal rack member, the rack member of said main template being generally of oblong

shape, the rack members of said auxiliary templates being of arcuate shape, means for moving each of said auxiliary templates relatively to said main template to cause them to be superposed over the adjacent ends of the main template, the teeth of said pinion being adapted to mesh with the teeth of said rack members, and means for rotating said pinion and guiding it around said rack members.

8. A buttonhole attachment for sewing machines comprising a supporting plate, a feed blade mounted thereon for oscillatory and sliding movements with respect thereto, a lever pivotally mounted on said plate, a pinion rotatably mounted on said lever, a supporting structure carried by the feed blade, a main template slidably carried by said structure, a pair of auxiliary templates slidably mounted in said structure for movement each in a linear path relatively to the main template, one adjacent each end of said main template, each of said templates being provided with an internal rack member, the rack member of said main template being generally of oblong shape, the rack members of said auxiliary templates being of arcuate shape, means for moving each of said auxiliary templates relatively to said main template to cause them to be superposed over the adjacent ends of the main template, the teeth of said pinion being adapted to mesh with the teeth of said rack members, the rack member of said main template being of keyhole shape at one end, and said main template and one of the auxiliary templates being interconnected to be moved simultaneously in opposite directions to cause the arcuate rack of the auxiliary template to be moved over and beyond said end of keyhole shape of the rack member of the main template.

9. A buttonhole attachment for sewing machines comprising a supporting plate, a feed blade connected to the plate for back-and-forth sliding movements longitudinally thereof and for pivotal movements laterally thereof, means for effecting such movements comprising a supporting frame carried by the feed blade in a position spaced above the same, a lever pivoted on the supporting plate, a portion of which extends to a point between said supporting frame and the feed blade, a pinion rotatably carried by the extending portion of said lever, a main template slidably mounted in said supporting frame provided with an internal rack member, an auxiliary template slidably mounted in said supporting frame for movement in a linear path relatively to the main rack member and provided with an internal rack member of arcuate shape adjacent one end of said first rack member, said pinion being adapted to engage the teeth of said rack members, means for moving one of said rack members relatively to the other to effect superposition of said auxiliary rack member with respect to said main rack member, means for rotating said pinion, and means for guiding said pinion around said rack members and said auxiliary rack member when moved being adapted to vary the effective length of said main rack member.

10. A buttonhole attachment as in claim 9 wherein a guide plate is provided in said supporting frame having a face thereof disposed adjacent said rack member, said plate having a guiding groove in said face, and said pinion is provided with a spring-pressed plunger extending into said groove.

11. A buttonhole attachment as in claim 9 wherein a guide plate is provided in said supporting frame having a face thereof disposed adjacent said rack member, said plate having substantially parallel guide grooves therein and a rib separating said grooves, and said pinion is provided with a guide plunger extending into said grooves, and wherein said auxiliary template is provided with means to guide said plunger over said rib from one groove into the other.

12. A buttonhole attachment as in claim 9 wherein a guide plate is provided in said supporting frame having a face thereof disposed adjacent said rack member, said

plate having substantially parallel guide grooves therein and a rib separating said grooves, and said pinion is provided with a guide plunger extending into said grooves, and wherein said auxiliary template is provided with means to guide said plunger over said rib from one groove into the other, said last-named guide means comprising an inclined ramp adjacent each of said grooves and said plunger being spring-pressed whereby it may ride over said ramps.

13. A buttonhole attachment for sewing machines comprising a supporting plate, a feed blade connected to the plate for back-and-forth sliding movements longitudinally thereof and for pivotal movements laterally thereof, means for effecting such movements comprising a supporting frame carried by the feed blade in a position spaced above the same, a lever pivoted on the supporting plate, a portion of which extends to a point between said supporting frame and the feed blade, a pinion rotatably carried by the extending portion of said lever, a main template slidably mounted for linear movement in said supporting frame provided with an internal rack member, an auxiliary template slidably mounted for linear movement in said supporting frame and provided with an internal rack member of arcuate shape adjacent one end of said first rack member, said pinion being adapted to engage the teeth of said rack members, each of said templates having a series of teeth thereon, the teeth of one series being in spaced relation to those of the other, a pinion rotatably mounted on the supporting frame and engaging the teeth of both series to move them simultaneously in opposite directions, means for rotating said pinion, and means for guiding said pinion around the rack members, and the internal rack member of said auxiliary template being of a shape different from that of the rack member at the adjacent end of the main template.

14. A buttonhole attachment for sewing machines comprising a supporting plate, a feed blade connected to the plate for back-and-forth sliding movements longitudinally thereof and for pivotal movements laterally thereof, means for effecting such movements comprising a supporting frame carried by the feed blade in a position spaced above the same, a lever pivoted on the supporting plate, a portion of which extends to a point between said supporting frame and the feed blade, a pinion rotatably carried by the extending portion of said lever, a main template slidably mounted in said supporting frame provided with an internal rack member, an auxiliary template slidably mounted in said supporting frame

50

and provided with an internal rack member of arcuate shape adjacent one end of said first rack member, said pinion being adapted to engage the teeth of said rack members, each of said templates having a series of teeth thereon, the teeth of one series being in spaced relation to those of the other, a pinion rotatably mounted on the supporting frame and engaging the teeth of both series to move them simultaneously in opposite directions, means for rotating said pinion, means for guiding said pinion around the rack members, and the internal rack member of said auxiliary template being of a shape different from that of the rack member at the adjacent end of the main template, and said pinion-guiding means including a plate mounted with one face thereof adjacent the rack members and having parallel guiding grooves in said face and a plunger carried by the pinion extending into said grooves, a rib separating said grooves and having an opening therein through which said plunger passes, and a guide sector carried by the main template and adapted to be moved over said rib adjacent the opening therein to urge said pinion outwardly away from the rib.

15. A buttonhole attachment for sewing machines comprising a supporting plate, a feed blade connected to the plate for back-and-forth sliding movements longitudinally thereof, means for effecting such movements comprising a lever pivoted on said plate, a pinion rotatably mounted on the lever, a supporting frame carried by the feed blade in a position spaced above the same, a pair of templates slidably mounted in said supporting frame, one of said templates having an internal rack member enlarged at one end so as to be of keyhole form, the other of said templates having an internal rack member of arcuate shape, means for effecting relative movements of said templates to superpose said rack member of arcuate shape over that of keyhole shape, the pinion being adapted to engage the teeth of the rack members, a guide plate having a guide slot therein above said rack members, and a partitioning rib in said slot, and means carried by said first-named template to slidably embrace the end of, and vary the shape of, the rib adjacent the end of the rack member of keyhole form, and means for oscillating said lever and rotating said pinion.
